DISPLAY AND STORAGE STRUCTURE

Morris Rostau, Brookline, Mass.

Application June 23, 1950, Serial No. 169,801

9 Claims. (Cl. 312—270)

1

The present invention relates to display and storage structures more particularly of a type wherein the drawer and shelf portions are advantageously though not necessarily made of a substantially transparent substance as a suitable plastic.

An object of the invention has been to provide a storage and display assembly, or the like, including transparent walled drawers which, when in closed position, permit visual inspection of goods stored therein and at the same time, protect them from contamination by dust and dirt.

A further object has been to provide a storage and display structure wherein drawers of transparent material arranged one above another are separated by transparent shelves which also function as lids to protect the contents of each drawer when in closed position and the contents of a lower drawer when the next upper drawer is in open or withdrawn position.

A further object of the invention has been to provide an assembly of drawer and shelf units which provides a maximum storage and display space with a minimum of supporting and concealing structure so that the general appearance of the contents of the show case will be visible with the drawers closed thus necessitating only a minimum handling of the goods for closer inspection.

Further objects and beneficial or advantageous features of this invention will in part be noted in and in part appear from the following description and the appended drawings which describe and illustrate one form of construction embodying my invention. In said drawings,

Figure 1 is a fragmentary view in front elevation of a display and storage assembly;

Figure 2, a fragmentary view thereof with a lateral upright support removed to show shelves and drawers in side elevation;

Figure 3, a central vertical section on the line 3—3 of Figure 1, on enlarged scale and with the lid displaced upwardly from its normal position, indicated in dotted lines;

Figure 4, a central vertical section on the line 4—4 of Figure 2 on enlarged scale;

Figure 5, a top plan view on enlarged scale of the drawer portions of the storage and display case shown in Figures 1 and 2;

Figure 6, a bottom plan view on enlarged scale of the lid or shelf portions of the structure shown in Figures 1 and 2; and

Figure 7, a fragmentary view partly in horizontal section showing details of the rear corner

2

construction and the relationship of the drawer in closed position to its corresponding lid or cover.

Referring to the drawings, the display and storage assembly there shown includes drawers 5 *a* of molded and preferably transparent plastic, as styrene, arranged one above another and interposed separating members, as lids or shelves *b* also molded and of the same or similar material. The separating members *b* which serve 10 as shelves to support drawers immediately above them and as lids to cover drawers immediately below them are supported at their lateral edges, conveniently by horizontal rabbets 12 in spaced uprights 13 where they are held against end-wise displacement by any suitable means, such 15 as a face or cover plate 13a, Figure 1, or the like, which overlies front end portions of said separating members or shelves. Said drawer *a* and shelf *b* are advantageously made of suitable 20 transparent plastic, such as styrene for example, so that articles or goods stored in the drawers *a* are readily visible through the front walls thereof and, under some conditions, through the shelves or lids *b*.

25 As seen in Figures 3 and 4, the side and rear end walls of drawer *a*, when the latter is made of molded plastic, unite to form rounded corners, said side walls being slightly inclined outwardly from bottom to top to permit easier removal of the drawer from the mold. The top edge of 30 the rear wall 14 thereof is disposed at a level below that of the top edges of the side walls 15 which are thickened or reinforced, as at 16. Said side walls extend rearwardly to said rear wall 14 from a front wall 17 having its top edge in 35 a plane higher than that of said top edges of the side walls 15 and provided with a forwardly or outwardly extending hand hold and reinforcing member 18. A rear end upper portion of 40 each of said side walls ends short of rear wall 14 to form a rearwardly exposed vertical stop face 19 and a short top edge 20 of curved lateral contour which merges into the top edge surface of rear end wall 14.

45 As seen in Figures 4 and 5, the front wall 17 of drawer *a* extends laterally beyond the side walls 15 and preferably fits within the space between the upright facing and shelf retaining strips or pieces 13a. A reinforcing rib 21 extending across 50 the bottom of each drawer near its front end terminates in fin-like projections 22 which also serve to steady the drawer when in closed position. Said drawer is also provided with transversely spaced longitudinal bottom reinforcing and guiding ribs 23 which, as seen in Figure 4, ride in

grooves 24 formed between spaced reinforcing ribs 25 extending along and projecting above the top surface of shelf or lid b. With this arrangement of the reinforcing ribs of the drawer and its supporting shelf, the normal bottom surface of the drawer and the normal top surface of the shelf are spaced apart so that they are not worn or their transparency impaired by repeated in and out movement of the drawer in use.

As shown in Figures 4 and 6, the shelf or lid b is provided with a depending flange having a front end portion 26 (in dotted lines Figure 3) arranged with its top edge flush with the front top edge of shelf b and positioned to engage and overlap an upper portion of the inner surface of front wall 17 of the drawer a when the latter is closed. Side portions 27 of said flange extend rearwardly from the lateral ends of said front end portion thereof and substantially parallel with the lateral edges of the shelf and with adjacent side walls of the drawer to a point opposite the stop face 19 of said side walls. Here, as seen more clearly in Figure 7, a short portion of the depending flange turns outwardly to form an offset shoulder or stop 28 which engages stop face 19 of the drawer and thus limits rearward or closing movement thereof. Said depending flange also has a rear end portion connected at its ends to said shoulders 28 by corners of laterally rounded contour. The lower edge 29 of said rear end portion extends below the level of the top edge of rear wall 14 of the drawer and is arranged in overlapping contact with outer surface portions thereof when the drawer is in closed position. It is contemplated that the overlapping features above described of portions of the front and rear ends respectively of the shelf or lid in contact with portions of the front and rear walls respectively of the drawer serve to protect the contents thereof more effectively from impairment by dust and dirt. In effect, they provide a complete closure to the extent that, when the drawer is in closed position, the area of closing contact between various portions of the lid and adjacent portions of the drawer is substantial and substantially continuous.

In assembling a display and storage structure according to the present invention, the required separating members b are mounted with their lateral edges engaged in the rabbets 12 of uprights 13. The facing strips 13a are applied to the outer surfaces of said uprights and thereby extend across and retain end portions of said separating members b. The space between adjacent separating members is such that a drawer a of suitable dimensions will slide freely between them but without excessive play. Thus, when a drawer is closed various parts thereof above referred to are snugly engaged with adjacent parts of its corresponding lid; and openings for entry of dust and dirt are thereby reduced to a minimum.

A display structure as described above has in addition the advantages of lightness, pleasing appearance, and of flexibility in respect to the number of drawers conveniently grouped in a multiple drawer assembly. This affords economy not only in initial cost but in transportation to and installation at the place of use.

I claim:

1. Display and storage structure of transparent plastic material comprising in combination vertically spaced integrally formed shelves arranged one above the other, and an integrally formed drawer slidably supported on a lower shelf and having a front end wall, a rear end wall and

spaced side walls, the next upper one of said shelves providing a cover for said drawer and having a flange extending downwardly from its under surface into said drawer, longitudinally extending portions of said flange being spaced inwardly from the side edges of said shelf and overlapping upper edge portions of the side walls of said drawer, a front end portion of said flange extending transversely across the front end of said shelf and opposite an upper portion of the front end wall of said drawer, and a rear end portion of said flange extending transversely across the rear end edge of said shelf and having a portion overlapping an upper edge portion of the outer face of said rear end wall of the drawer.

2. Structure according to claim 1 and wherein the top edge of the front end wall of said drawer is in a plane above the plane of the top edges of the side walls thereof and the top edge of the rear end wall is in a plane below said plane of the top edges of said side walls of the shelf.

3. Structure according to claim 1 and wherein an upper edge portion of the front wall of the drawer overlaps and engages said front end portion of the shelf flange.

4. Structure according to claim 1 and wherein longitudinally extending portions of said flange of the shelf extend across and slidably engage top edge portions of the drawer and connect the front end transverse portion of said flange with said rear end transverse portion thereof.

5. Structure according to claim 1 and wherein the flange of said cover is continuous and is arranged with said rear end transverse portion extending downwardly outside of said drawer and the other portions extending downwardly inside of said drawer.

6. Structure according to claim 1 and wherein said flange has a lateral offset arranged between a rear end of each longitudinally extending portion of the flange and the corresponding ends of the rear transversely extending portion of said flange and said drawer has rearwardly exposed vertical stop faces to engage said offset when the drawer is in closed position.

7. Display and storage structure comprising in combination a plurality of drawers each integrally formed of transparent plastic material and slidably supported between vertically spaced partition members which are integrally formed of transparent plastic material, each said member being a cover for a drawer below it and a shelf for supporting a drawer above it, said drawers having their bottom surfaces provided with longitudinally extending downwardly directed ridges and said partition members having their top surfaces provided with longitudinally extending upwardly directed ridges cooperating with said downwardly directed ridges to guide said drawers during movement thereof into and out of open position and to space the normal bottom surface of a drawer from the normal top surface of its supporting partition member.

8. Display and storage structure according to claim 7 and wherein the rear end wall of each drawer joins a portion of each of the side walls thereof to form rounded rear corners and each partition member has a continuous flange with its side and front end portions extending downwardly into the drawer below said member, said side portions positioned to be slidably engaged by the upper edge of said rounded corner of the drawer when the latter is moved in and out, said front end portion being flush with the front edge of said member, and a rear portion overlapping

top edge portions of the rear end wall of the drawer, said rear portion having its ends rounded to conform to and closely engage rounded rear corner portions of the drawer when the latter is in closed position.

9. Display and storage structure according to claim 7 and wherein front edge portions of each partition member engage upper portions of the inner surface of the front wall of the drawer next below said member and rear edge portions of said partition member overlap upper portions of the outer surface of the rear wall of said drawer, said rear edge portion having its ends rounded to conform to and closely engage rounded rear corner portions of the drawer 15 when the latter is in closed position.
